(57) **CLAIM**

The ornamental design for hand tool sleeve with symbol, as shown and described.

DESCRIPTION

FIG. 1 is an enlarged, partial front view of a hand tool sleeve with symbol showing our new design;

FIG. 2 is a front view of a hand tool sleeve with symbol;

FIG. 3 is a side view thereof;

FIG. 4 is a rear view thereof;

FIG. 5 is an opposite side view thereof;

FIG. 6 is a bottom view thereof;

FIG. 7 is a top view thereof; and,

FIG. 8 is a front, side and bottom perspective view thereof.

The broken lines depict portions of the hand tool sleeve with symbol that form no part of the claimed design.
